COMBINED EXTENSIBLE TUBE, BRACKET AND CLOSURE FOR A LUBRICATING CAN OR THE LIKE

Robert H. Porter, 9049 Infirmary Road,
Portage County, Ohio

Filed Dec. 31, 1962, Ser. No. 73,014

Term of patent 7 years

(Cl. D58—26)

FIG. 1

FIG. 2

FIG. 3

FIG. 1 is a perspective view of a combined extensible tube, bracket and closure for a lubricating can or the like, showing my new design;

FIG. 2 is an elevational view thereof on an enlarged scale; and

FIG. 3 is a top plan view thereof on an enlarged scale. The can shown in broken lines in FIGS. 1 and 2 is for illustrative purposes only.

I claim:

The ornamental design for a combined extensible tube,

bracket and closure for a lubricating can or the like, substantially as shown and described.
